RECEPTACLE

Harry Negbaur, New York, and Robert Nyden,
Long Island City, N. Y., assignors to H. Negbaur & Co., Inc., New York, N. Y., a corporation of New York.

Application June 29, 1938, Serial No. 216,454

15 Claims. (Cl. 206—41)

The present invention relates to receptacles, and is more particularly directed toward receptacles designed to be used as holders for cigarette packages.

The present invention contemplates a device for the above purposes adapted to receive a package of cigarettes and having a closure member which covers the open end of the package.

According to the preferred form of the present invention the device has a body member made out of resilient sheet material, preferably some form of sheet metal which may be pierced, ornamented, or decorated in any desired manner, and a closure member suitably secured to the body member and adapted to be swung back and forth over the open end of the body member to permit access to the enclosed package, or to cover it. The closure member and the body member are secured together by a mechanism which functions to cause the closure member to be held normally closed, but which, upon the application of external pressure, as, for example, by squeezing the side walls of the body member, causes the closure member to swing to the open position. Instead of squeezing the side walls of the body member, the closure member may be swung to the open position by engaging it with the finger or thumb of the hand holding the device. In either case the spring tension inherent in the construction of the body member effects immediate closure of the device upon the release of external pressure.

The present invention also contemplates a receptacle for the purposes stated having stiff substantially unyielding walls and a closure member adapted to swing away from the opening and having a spring to shift it to the closed position.

A further object of the invention is to provide devices of this nature in which the operating mechanism is small and compact and has no external elements likely to catch in the pocket or interfere with its operation.

A further object is to provide the device with suitable stops which limit the movement of the parts in either extreme position.

The accompanying drawing shows, for purposes of illustrating the present invention, two of the many embodiments in which the invention may take form, it being understood that the drawing is illustrative of the invention rather than limiting the same.

In the drawing:

Figure 1 is a perspective view of the receptacle showing it in the open position;

Figure 2 is a side elevational view of the same

with the closure member in the closed position and parts broken away to show interior construction;

Figure 3 is an end elevational view of the structure shown in Figure 2 with parts broken away;

Figure 4 is an enlarged sectional view on the line 4—4 of Figure 2, the closure member being in closed position;

Figure 5 is a view similar to Figure 4 with the closure member in the open position;

Figure 6 is a fragmentary sectional view on the line 6—6 of Figures 3 and 4 and showing in dotted lines the relative position of the side members when the closure member is in the open position; and

Figure 7 is a fragmentary sectional view through a modified form of construction.

The body member 10 is made out of a single piece of sheet material preferably by a stamping operation. It has sides 11 and 12, which may be solid or apertured to show the sides of the enclosed package, and also a bottom 13 interconnecting the sides. The edges of the sides have opposed flanges which extend toward one another. These flanges have comparative narrow lower portions 14, 14' and wide overlapping portions near the top, as indicated at 15 and 16. The flange 16 is nearer the bottom of the body member than the flange 15, and has an offset portion 17 which passes behind the lower edge 15 of the flange 15, and the flange 15 has an end portion 18 which is offset and passes behind the upper edge 16' of the flange 16. This will be apparent from Figure 4 of the drawing. The offsets referred to provide stop members or shoulders 17' and 18' which are normally spaced apart, as shown in Figure 4. The flange members 15 and 16 carry outwardly extending elements preferably in the form of pins 19 and 20. The cover or closure member 21 is provided with downwardly extending sides or arms 22 and 23 which pass down outside the flanges 15 and 16. They are provided with diagonal slots, indicated at 24, to receive the outwardly extending pins 19 and 20.

When the body member is stamped up it is provided with a tension which tends to spread the side walls 11 and 12 somewhat farther apart than indicated in the drawing, so that when the side walls are brought to the positions indicated in Figures 1, 3, 4 and 6, some tension is developed in the resilient material employed. This tension tends to separate the side walls and through the movement of the pins 19 and 20 in the slots 24 exerts a turning moment on the closure member 21 causing it to be held in the position shown in

Figures 2, 3 and 4. When in this position the left edge 25 of the closure member abuts the upper end of the side wall, as indicated at 26. At this time the free edge 27 is adjacent the free edge 28 of the other side wall.

When one applies pressure, as indicated by the arrows at the opposite sides of Figure 3 or by the hand as illustrated in dotted lines in Figure 1, the side walls 11 and 12 are forced toward one another. This will cause the pins 19 and 20 to shift from one side of the plane indicated by the dotted line a—a of Figure 4 to the opposite side of the plane indicated by the said line as shown in Figure 5. During this shifting of the pins past one another they traverse the slots 24 and cause the closure member to swing from the position shown in Figure 4 to the position shown in Figures 1 and 5. This effects an opening of the top of the case permitting access to the cigarettes in the package as will be obvious from Figure 1. Owing to the cutting away of the upper flanges above the overlapping portions 14 and 15, space is provided for grasping the first cigarette to be removed, also for grasping the empty wrapper for removing it from the case. The amount of movement which can be had by squeezing the side walls is controlled by the engagement of the shoulders 17' and 18' with the edges 15' and 16' of the flange elements, as will be clear from Figure 5.

The flanges carried by the side walls provide convenient guides to facilitate placing the package of cigarettes in the case and suitably reinforce the side walls, so that they are not likely to become collapsed or bent out of shape. The narrow flange 13' bent up out of the bottom wall 13 also acts as a stiffening member, but preferably the flanges 13', 14 and 14' are separated by narrow gaps or spaces 25, as indicated in Figure 3, so as not to unduly stiffen the structure. A finger hole 13" facilitates removal of the package from the holder.

Instead of manipulating the cover to the open position by squeezing the side walls of the holder, as indicated in Figure 1, it is, of course, obvious that one can hold the carrying case in the palm of the hand and use the thumb to swing the closure member to open position. Should the aperture in the side walls be large, the margins may be squeezed.

In the arrangement shown in Figure 7 the holder has sides 30 and 31 and end walls one of which appears at 32. The end walls have pivot members, indicated at 33, to which is pivotally supported a cover or closure member 34 having downwardly extending sides 35 secured on the pivots 33. Between the end walls 32 of the body member and the downwardly extending sides 35, springs 36 are secured as indicated. These springs are tensioned to hold the cover in the closed position indicated in full lines and yet permit the cover to swing to the dot-and-dash line position.

It will be noted in both forms of construction the cover is pivoted close to the upper end of the body member and yet is arranged so as to swing entirely clear, so that the cigarette package can be readily inserted.

It is obvious that the invention may be embodied in many forms and constructions within the scope of the claims and we wish it to be understood that the particular forms shown are but two of the many forms. Various modifications and changes being possible, we do not other-

wise limit ourselves in any way with respect thereto.

What is claimed is:

1. A holder for cigarette packages comprising a body member of resilient sheet material having an open upper end adapted to receive a package of cigarettes with the upper end exposed and having sides tensioned to spread away from the sides of the package and opposed flanges adjacent the open end, and a closure member having a portion adapted to cover the exposed end of the package and downwardly extending ends connected with the flanges to hold the sides of the body member compressed when the closure member is closed, whereby the closure member is held closed, and to further compress the sides when the closure member is opened.

2. A holder for cigarette packages such as claimed in claim 1, wherein one edge of the closure member abuts the upper edge of one of the sides when the closure member is in closed position.

3. A holder for cigarette packages such as claimed in claim 1, wherein the opposed flanges have stop elements which limit the movement of the sides toward one another and the swinging of the closure member to the open position.

4. A holder for cigarette packages such as claimed in claim 1, wherein the opposed flanges pass by one another and have outwardly extending elements at different distances from the bottom wall of the body member and at opposite sides of a median plane between the sides of the body member when the closure member is in closed position, and shifting across said plane when the closure member moves to open position, and wherein the closure member has a lost motion connection with the said elements.

5. A holder for cigarette packages such as claimed in claim 1, wherein the opposed flanges pass by one another and have outwardly extending elements at different distances from the bottom wall of the body member and at opposite sides of a median plane between the sides of the body member when the closure member is in closed position, and shifting across said plane when the closure member moves to open position, and wherein the closure member has oblique slots into which the pairs of outwardly extending elements extend.

6. A holder for cigarette packages such as claimed in claim 1, wherein the opposed flanges have stop elements which limit the movement of the sides toward one another and the swinging of the closure member to open position, and the flanges pass by one another and have outwardly extending elements at different distances from the bottom wall of the body member and at opposite sides of a median plane between the sides of the body member when the closure member is in closed position, and shifting across said plane when the closure member moves to open position, and wherein the closure member has a lost motion connection with the said elements.

7. A holder for cigarette packages comprising a body member having sides interconnected by a bottom and provided with inwardly directed flanges at the edges of the sides, the body member being adapted to receive through its open top a package of cigarettes with their ends adjacent the open top of the body member, and being made of resilient sheet material and tensioned to spread the sides to a predetermined spacing, and a cover overlying the top of the body member and the inserted package and hav-

ing a lost motion hinge connection with each of the flanges of each pair, the resilient sides acting as springs to hold the cover in the closed position and being bendable toward one another when the cover is being opened.

8. In a holder for cigarette packages, a body member having sides interconnected by a bottom and provided with inwardly directed flanges at the edges of the sides, the body member being adapted to receive through its open top a package of cigarettes with their ends adjacent the open top of the body member, and being made of resilient sheet material and tensioned to spread the sides to a predetermined spacing, the opposed flanges having stop shoulders which limit the movement of the sides toward one another.

9. In a holder for cigarette packages, a body member having sides interconnected by a bottom and provided with inwardly directed flanges at the edges of the sides, the body member being adapted to receive through its open top a package of cigarettes with their ends adjacent the open top of the body member, and being made of resilient sheet material and tensioned to spread the sides to a predetermined spacing, the opposed flanges having stop shoulders which limit the movement of the sides toward one another, and a cover member overlying the top of the body member and the inserted package and having lost motion hinge connections with each of the flanges adjacent each of the stop shoulders.

10. A holder for cigarette packages comprising a body member having sides interconnected by a bottom and provided with inwardly directed flanges at the edges of the sides, the body member being adapted to receive through its open top a package of cigarettes with their ends adjacent the open top of the body member, and being made of resilient sheet material and tensioned to spread the sides to a predetermined spacing, and a cover overlying the top of the body member and the inserted package and interconnected with the flanges to impose a predetermined compression in the sides when the cover is in the closed position and an additional compression when the cover is swung by the application of an external force to the open position to expose the top of the package, whereby upon the release of the external force effecting said additional compression the resilient sides act as springs to move the cover to closed position.

11. A receptacle having opposite sides yieldably movable toward and away from one another, two pairs of inwardly extending opposed members

carried by said sides, and having outwardly extending pivot elements adapted to shift past one another as the sides are moved back and forth, and a closure member adapted to overlie the ends of the sides and said members and having slotted ends which receive the pivot elements, the pivot elements sliding in the slots as the sides are moved back and forth and effecting a swinging of the closure member to cover or uncover the receptacle.

12. A receptacle such as claimed in claim 11, wherein the closure member has an edge engaging the free edge of one of the sides when the member is in closed position.

13. A receptacle such as claimed in claim 11, wherein the opposed members have stop elements which limit the approach of the sides toward one another and the swinging of the closure to the open position.

14. A rectangular receptacle having an open mouth at the top, and a closure member having ends extending down alongside two opposite side walls of the receptacle and pivoted thereto at points spaced below the open mouth a distance which will permit the entire closure member to swing past the upper edge of one of the other side walls and be brought down alongside said wall, and wherein said other side walls are resilient to form spring means acting to hold the closure member in closed position.

15. A rectangular receptacle adapted to receive a package of cigarettes with the upper end of the package open and having an open mouth at the top to give access to the upper ends of the cigarettes, a closure member having side arms extending down alongside the two opposite side walls of the receptacle adjacent the shorter sides of the package and pivoted thereto at points spaced below the open mouth a distance which will permit the entire closure member when swung through an angle of substantially 90° to pass by the upper edge of one of the longer side walls and be brought down alongside said longer side wall, the upper ends of the shorter side walls being cut out to provide finger openings to facilitate removal of a cigarette from the package and of the empty package, the width of the side arms being greater than the width of the finger openings to cover the same when the closure member is in closed position, and spring means acting to hold the closure member in closed position.
